Specification for Design.

Patented May 24, 1921.

Application filed February 28, 1920. Serial No. 362,124. Term of patent 14 years.

To all whom it may concern:

Be it known that I, GENEVIEVE PFEFFER, a citizen of the United States of America, and resident of San Jose, California, have invented a new, original, and ornamental Design for an Apron, of which the following is a specification, reference being had to the accompanying drawing, in which—

Figure 1 shows a front view of the apron, Fig. 2 a rear view thereof, and Fig. 3 the garment when laid flat.

I claim:

The ornamental design for an apron, substantially as shown.

GENEVIEVE PFEFFER.
